UNITED STATES PATENT OFFICE.

WILLIAM M. FISHER, OF CINCINNATI, OHIO, ASSIGNOR TO AMERICAN BOILER AND FURNACE COMPANY, OF SAME PLACE.

STEAM-BOILER.

SPECIFICATION forming part of Letters Patent No. 228,521, dated June 8, 1880.

Application filed March 25, 1880. (No model.)

To all whom it may concern:

Be it known that I, WILLIAM MACK FISHER, a citizen of the United States, residing at Cincinnati, in the county of Hamilton and State 5 of Ohio, have invented certain new and useful Improvements in Steam-Boilers, Boiler-Furnaces, Evaporators, &c.; and I do hereby declare the following to be a full, clear, and exact description of the invention, such as will enable others skilled in the art to which it 10 pertains to make and use the same, reference being had to the accompanying drawings, and to letters or figures of reference marked thereon, which form a part of this specification.

15 This invention is an improvement on the invention described in United States Letters Patent No. 225,051, granted to me on the 2d day of March, A. D. 1880, and was devised with a view of effecting a still more thorough 20 combustion and consumption of the combustible gases proceeding from a steam-boiler, furnace, or other fluid heating and evaporating furnace, and increasing the circulation of the fluid to facilitate and hasten its vaporization 25 or evaporation by a more constant generation of vapor.

To these ends the improvement consists, mainly, in the application to the boiler of an additional legged fluid-partition, one or more, 30 depending into the second or supplementary combustion-chamber, so as to compel the hot gases (the main volume thereof) to pass in a tortuous direction through this supplementary combustion-chamber, retarding them sufficiently to supply them with the needed amount 35 of atmospheric oxygen to complete combustion. The additional legged fluid-partition effects at the same time an increase of circulation of the contents of the boiler.

40 In order that my improvement may be clearly understood, I will proceed to give a detailed description of the same as applied to a steam-boiler and an evaporator respectively, in connection with the annexed drawings, of 45 which—

Figure 1 is a sectional perspective view of a horizontal flue-boiler embodying my improvement. Fig. 2 is a transverse vertical section of said boiler, the section being taken in the 50 plane indicated by broken line α of Fig. 1.

Fig. 3 is a sectional perspective view of an evaporator embodying my improvement.

A refers to an ordinary horizontal flue-boiler for generating steam, suitably set in masonry. The fire-chamber B, in the example illustrated, 55 is adapted for the burning of lump coal and similar fuel.

It may be remarked, however, that my invention may be used with equal advantage in steam-boiler and other furnaces adapted for 60 the burning of other kinds of fuel, such as liquid fuel or coal-dust.

The lump coal is burned on the grate-surface B', under which there is the usual ash-pit B².

The back or rear end of the fire-chamber B is formed by the hollow partition C, constructed at its respective ends with hollow legs C' and C², by which it is connected with the boiler. Leg C', covering an opening in the shell of 70 the boiler, communicates with the lower portion of the water therein. Leg C² extends up into the water-space of the boiler, and its open upper end may terminate either in the steam-space thereof or in the water-space near the 75 water-line, as shown. The main volume of the flame and gases proceeding from the fire-chamber passes over the top of this partition through the passage-way C³ between its legs, and the balance through the narrow passages 80 between said legs and the side walls of the fire-chamber.

The partition C extends down to the grate-surface. The narrow passages between the legs of the partition and the side walls are of 85 advantage in distributing the heat more uniformly over the whole surface of the legged partition.

A second or supplementary combustion-chamber, D, is formed between the hollow- 90 legged partition C and the bridge-wall E. This chamber D has a perforated bottom, D', through which atmospheric air enters in jets to mingle with the products of combustion passing through this chamber, and supply the 95 necessary oxygen for the ignition of combustible gases not previously ignited or in an incomplete state of combustion. A second hollow-legged partition, F, depends from the boiler into this chamber D, differing from the 100

partition C only in not extending down to the bottom of the chamber, and having its top edge pretty close up to the bottom of the boiler. This pendent hollow-legged partition compels 5 the main volume of flame and gases to travel in a tortuous direction through the supplementary combustion-chamber, so that the gases are retained therein long enough to supply them with all the atmospheric oxygen needed 10 to complete combustion. This function of the second water-partition is necessarily accompanied by an increase of heat in the supplementary combustion-chamber, which is measurably compensated for by the rapid absorption 15 of heat by this pendent water-partition.

By reason of their described legged construction, the water-partitions are very effective circulators, the less-heated water constantly descending one leg, while the more highly- 20 heated mingled steam and water as constantly ascend the other leg. Hence the generation of steam in them will be uniformly constant, and overheating and consequent sudden eruptions of steam be avoided. The circulation of 25 water through the water-partitions necessarily effects a more or less active circulation of the water in the boiler, and this may be increased by the application of one or more pendent water-partitions, like the one (marked F) beyond 30 the bridge-wall E. One such additional pendent partition is shown in dotted lines in Fig. 1. The water-partitions may be so arranged that the long legs of two adjacent ones shall be on opposite sides of the boiler, as shown in Fig. 35 1. The pendent water-partition in the supplementary combustion-chamber and those beyond the bridge-wall, if used, may be arranged at an angle of declination, if deemed expedient.

As a matter of course, the invention is applicable to the various kinds of portable and 40

stationary boilers, including locomotive and marine boilers. It may also be applied with advantage to evaporating-pans, vats, stills, and the like. Fig. 3 illustrates an instance of its use in connection with an evaporating-pan, 45 G, placed over a furnace similar in construction to the boiler-furnace shown in Figs. 1 and 2. The legged water-partitions C and F are connected to the superimposed reservoir H, so that the fluid therefrom will circulate through 50 said partitions.

What I claim as my invention, and desire to secure by Letters Patent, is—

1. The combination, substantially as before set forth, of a steam-boiler or other means for holding a fluid to be vaporized or evaporated, the fire-chamber, the hollow partition at the rear end of the fire-chamber, and constructed with hollow legs, one of which opens into the lower part of the water-space, while the other 60 extends to the steam-space, or thereabout, and one or more pendent hollow similarly legged partitions beyond the fire-chamber.

2. The combination, substantially as before set forth, of a steam-boiler or other means for holding fluid to be vaporized or evaporated, the fire-chamber, the hollow partition at the rear end of the fire-chamber, and constructed with hollow legs, one of which opens into the lower part of the water-space, while the other 70 extends to the steam-space, or thereabout, the second combustion-chamber, and a pendent hollow similarly legged partition in said second combustion-chamber.

In testimony whereof I affix my signature 75 in presence of two witnesses.

WILLIAM MACK FISHER.
